DEVELOPING APPARATUS

Alexander J. Singer, Seat Pleasant, Md.

Application May 5, 1950, Serial No. 160,239

2 Claims. (Cl. 95—100)

1

This invention relates to photography, and more particularly to new and useful improvements in tanks for developing roll film.

The principal object of the invention is to provide an improved form of developing apparatus with a film holder which requires no adjustment when used for anyone of the popular sizes of roll films.

Another object of the invention is to provide a developing apparatus which is simple and economical to manufacture and which consists solely of two parts.

Still another object of the invention is to provide a developing apparatus which is simple to use in developing roll films.

Another object of the invention is to provide a developing apparatus with a detachable film holder on which any desired length of roll film may be easily and quickly attached.

The invention embodies an elongated tank body of rectangular cross-section to which is detachably connected a film holder. The latter is provided on one end with an open-ended head member the opening of which is equipped with light arresters to prevent light from entering the tank body when the film holder is attached to the latter. The light arresters also allow free entry of liquid in filling the tank body but offer a slight resistance when the liquid is poured from the tank body.

The various features of novelty which characterize the present invention are pointed out specifically in the claims annexed to and forming a part of this specification. For a better understanding of the invention, however, its advantages and specific objects attained with its use, reference should be had to the accompanying drawings and the description which illustrate and describe a preferred embodiment of the invention.

In the drawings:

Figure 1 is an isometric view of a preferred embodiment of the developing device of my invention;

Figure 2 is a cross-sectional view taken along line 2—2 of Figure 1, looking in the direction of the arrows;

Figure 3 is a vertical sectional view taken along line 3—3 of Figure 1, looking in the direction of the arrows, with a film in place; and,

Figure 4 is a vertical sectional view of the film holder when removed from the tank body and taken along line 4—4 of Figure 3.

Referring more particularly to the various figures of the drawing in which like reference char-

2

acters indicate the same parts, the developing device comprises a tank body 6 and a film holder 7. The tank body 6 is relatively long with respect to its rectangular cross-section. These parts may be made of metal, plastic, rubber, or any other suitable material which is opaque and is not affected by developing solutions or any other solutions used in developing and treating photographic films.

10 The tank body 6 is of such a size that the popular sizes of roll film may be suitably developed, washed and fixed therein. The film holder 7 requires no adjusting to hold the film. A cover or open-ended head member 8 is integrally formed with one end of the film holder, as shown in Figures 1, 3 and 4. The head member 8 is of larger cross-sectional area than the tank body 6 and comprises a circumferential vertical wall formed with a shoulder 5 at its lower end from which a slot or groove 9 extends inwardly and lengthwise of the member 6 to form a circumferential pocket for receiving the upper edge of the tank body 6 when the holder 7 is inserted into the tank body. It is obvious that in this manner 15 a light tight joint is formed between the head member 8 and the tank body 6.

The lower portion of the film holder 7 is I-shaped in cross-section and is provided on the opposite faces of its web section 11 with a plurality of uniformly spaced semi-circular ribs 10 which preferably are integrally formed with the holder. The ends of the ribs are spaced from the longitudinal flanges 12, as shown. The flanges 12 are connected with opposite end walls 13 of the head member 8, as shown in Figure 4. 20 The flanges 12 preferably are spaced from the side walls and end walls of the tank body 6 when the holder is inserted in the tank. Although it is preferred to form the ribs 10 as shown, it is to be understood that the ribs 10 may have any other shape as long as the ribs provide a space for the liquid used to develop and flush the film 14 attached to the holder 7. The semi-circular ribs serve the dual function of preventing the 25 film from adhering to the film holder and to promote agitation when the film is washed.

The open-ended head member 8 is provided with integrally formed light arresters 15 as shown in Figures 3 and 4. The light arresters extend 30 the full width of the rectangular opening in the head member 8 and are alternately vertically spaced and arranged to overlap with their free margins to prevent light from entering the tank body 6 during the developing of the film. The 35 light arresters 15 allow for the free entry of the

liquid but are arranged to extend at an acute angle inwardly so as to offer a slight resistance when the liquid is being poured from the tank in order to create an agitating effect when washing the film. A vertical transverse partition 16 integrally formed with the head member 8 and extending across the light arresters 15 and parallel to one end wall provides a vent 17 to eliminate air binding when filling the tank body with liquid. The larger portion 18 of the opening of the head member 8 serves for filling and emptying the tank body.

In utilizing the developing tank, the film holder 7 is first removed from the tank body 6. Most roll films have a water-proof adhesive tape 19 at one end, and by means of this tape the film is secured with the sensitized side out to the film holder 7 just below the head 8 to the web 11 of the film holder as shown in Figure 3. The roll film is then extended down to the bottom end of the holder 7 and is brought around to the other side of the web 11 to be affixed with its other end by means of another piece of adhesive tape 19. In this manner the film 14 may be quickly and easily attached to the holder 7 even in total darkness which is necessary with some types of films.

The film holder 7 with the film attached thereto is then inserted in the tank body 6. Developing fluid is then poured into the opening 18 to the level indicated with 20 in Figure 3. The film is then suitably developed as is well understood in the art and liquid may be suitably agitated. After the film has been treated the required length of time the developing fluid is poured from the opening 18, after which a washing fluid is poured into the tank and removed again to be replaced by a fixing solution to fix the film in the usual manner. In filling and emptying of the developing tank, the vent 17 prevents air binding. Furthermore, with this construction after the film has once been positioned in the developing tank, the developing, washing and fixing may be accomplished in daylight or ordinary room lighting and total darkness is no longer required.

It is thus obvious that a developing tank has been disclosed which is not only particularly desirable for developing of long roll film which need to be positioned on both sides of the holder, but also is equally desirable for shorter roll films which may be attached to one side of the frame only.

Furthermore, a simple developing tank has been disclosed in which no adjustments are required for different sizes and lengths of roll film. Obviously, also, as there are no movable parts and since the device comprises only two parts, a developing tank has been provided which may be simply and quickly operated.

In addition the developing tank may be constructed very economically, is simple to load with film in the darkness and may thereafter be used in daylight without the film becoming fogged.

While in accordance with the provisions of the statutes, I have illustrated and described the preferred embodiment of my invention now known to me, it will be apparent to those skilled in the art that changes may be made in the form of

the parts of the developing device disclosed and in the arrangements of the several details without departing from the spirit of the invention as long as these changes remain within the scope of the claims accompanying this specification.

What I claim is:

1. A film holder for a developing tank comprising an elongated member of I-shaped cross section and a cover provided with a rectangular opening integrally formed with one end of said elongated member, said cover having an outwardly directed shoulder where it is connected with said elongated member, said shoulder being provided with a continuous groove for receiving the upper edge of a developing tank into which said film holder is adapted to be inserted, the I-shaped cross section of said elongated member having flanges between which a web section is positioned on which a film strip to be developed is adapted to be secured, one end of said flanges being connected with said cover inside the area circumscribed by said continuous groove, light arresting ribs extending along the entire width of said opening and a transverse partition being provided in the opening of said cover, near one of the narrow walls of the same to form a light-proof vent.

2. A film holder for a developing tank comprising an elongated member of I-shaped cross section and a cover provided with a rectangular opening integrally formed with one end of said elongated member, the opening in said cover being substantially as wide as the largest dimension of the cross section of said elongated member, said cover having an outwardly directed shoulder where it is connected with said elongated member, said shoulder being provided with a continuous groove for receiving the upper edge of a developing tank into which said film holder is adapted to be inserted, the I-shaped cross section of said elongated member having flanges between which a web section is positioned on which a film strip to be developed is adapted to be secured, one end of said flanges being connected with said cover inside the area circumscribed by said continuous groove, light arresting ribs extending along the entire width of said opening and a transverse partition being provided in the opening of said cover, near one of the narrow walls of the same to form a light-proof vent.

ALEXANDER J. SINGER.
